By Robert Burns Helly.

UNITED STATES PATENT OFFICE.

ANTHONY JEROME, OF CHICAGO, ILLINOIS, ASSIGNOR TO THE A. FEATHERSTONE & COMPANY, OF SAME PLACE.

REAR-FORK END FOR CYCLES.

SPECIFICATION forming part of Letters Patent No. 622,006, dated March 28, 1899.

Application filed November 7, 1898. Serial No. 695,788. (No model.)

To all whom it may concern:

Be it known that I, ANTHONY JEROME, a citizen of the United States, residing at Chicago, in the county of Cook and State of Illinois, have invented certain new and useful Improvements in Rear-Fork Ends for Cycles; and I do hereby declare the following to be a full, clear, and exact description of the same, reference being had to the accompanying drawings, forming a part of this specification.

The present invention relates to a fitting for connecting together the rear-fork tubes of bicycles and the like and affording a support for the axle of the rear wheel thereof.

The object of the present improvement is to provide a simple and efficient formation and arrangement of parts whereby a strong and durable junction of the parts is effected in a ready, certain, and economical manner, as will hereinafter more fully appear and be more particularly pointed out in the claims. I attain such object by the construction of parts illustrated in the accompanying drawings, in which—

Figure 1 is an elevation of the inner side of the present improved fork end; Fig. 2, a similar view of the outer side of the same; Fig. 3, an elevation of the flat connecting-plate member with the thimbles or sockets ends in section at line $x-x$, Figs. 5 and 6; Fig. 4, an enlarged detail section at line $x'-x'$, Fig. 1; Figs. 5 and 6, enlarged detail sections at lines x^2-x^2 and x^3-x^3 , respectively, Fig. 1; and Fig. 7, an enlarged detail section illustrating a modified form of the connecting or pivoted stud on the plate member and which has engagement in orifices in the thimbles or sockets.

Similar numerals of reference indicate like parts in the several views.

Referring to the drawings, 1 represents the connecting-plate of the present invention of a flat formation and formed with an open-ended slot 2 for the axle, a pair of divergent prongs 3 and 4, and pivot-studs 5 and 6 at the base of such divergent prongs.

In the present improvement each divergent prong will consist of an outer tongue portion 7 and semicircular base portion 9 10, the pivot-studs 5 and 6 having a concentric arrangement with relation to the semicircular border of such base portions of the divergent

prongs, the construction being such that the alinement of the parts is very perfectly preserved during the brazing operation, and in the case of the adjustable prong 3 the adjustment thereof can be readily effected without danger of disturbing the concentric relation between the end of such prong and the semicircular base portion of the connecting-plate. The abutting ends of the prongs will also be 60 preferably milled out to fit the convexity of such semicircular base portions of the connecting-plate for a more perfect attainment of the above-stated purpose.

In the preferred construction of the present improvement, as illustrated in the drawings, the tongue portion 7 of the upper prong will have tapering or wedge-shaped formation, as shown in Figs. 1 and 3, so as to admit of a limiting rocking movement of the 70 thimble that fits thereon in the process of assembling the parts previous to the brazing operation and in order to attain the proper adjustment of the thimbles with relation to each other in using the present fork end in constructing different heights of bicycle-frames. The other and lower tongue portion 8 will be of a straight or parallel edge formation, as shown, so as to snugly fit the interior of the thimble that is arranged thereon with little 80 or no play.

The pivot or connecting studs 5 and 6 may be integrally formed with the connecting-plate 1 during the process of stamping the same, as shown in Fig. 4, or the same may be 85 in the form of a separate stud 5', riveted in place in said plate, as shown in Fig. 7.

The thimbles or sockets 11 and 12 of the present invention will preferably be made each in the form of a sheet-metal stamping, 90 and will comprise an outer reduced attaching-neck 13 14 and an enlarged base portion 15 16, a material part of the present invention being the formation of such thimbles of a tubular form, D-shaped in cross-section, as 95 shown in Figs. 5 and 6, in that the flat inner surface of thimbles so formed affords a large and effective surface upon which to braze the adjacent faces of the respective prongs 3 and 4 of the main connecting-plate, and so afford 100 a strong and substantial attachment of the parts.

In the present construction the prongs 3 and 4 have entrance into the interior of the respective thimbles through entrance-slits in the base portions of the same, which slits are milled out or otherwise formed in line with the flattened wall of the thimbles, as shown. The base portions 15 and 16 of said thimbles are preferably of a semiglobular shape, (illustrated in the drawings,) with their curved or 10 semicircular margin concentric with the pivot or connecting studs, as affording a neater finish, and at the same time with any pivotal adjustment of the upperthimble offer no interference with the application of the covering-plate that is commonly used in connection with the rear-fork ends of bicycles.

17 is a hole or orifice in the flat side of the thimbles, and which is adapted to engage the pivot or connecting studs on the connecting-20 plate 1 to insure an initial proper position of the parts previous to and during the brazing operation.

The seam 18 of the sheet-metal stamping that forms the thimbles 11 and 12 will usually 25 be arranged centrally on the flat portion or side thereof, as illustrated in Figs. 1, 5, and 6. Such seams may be arranged elsewhere, if found more convenient, without departing from the spirit of this part of my invention.

30 Having thus fully described my said invention, what I claim as new, and desire to secure by Letters Patent, is—

1. A rear-fork end for cycles, comprising a plate connection formed with a guide-slot for 35 the axle, and with diverging prongs, and thimbles having a D shape in cross-section and the flat portions which are adapted to contact with the adjacent flat surfaces of the prongs to afford extended brazing-surfaces 40 and a substantial attachment between the parts, substantially as set forth.

2. A rear-fork end for cycles, comprising a plate connection formed with a guide-slot for the axle and with diverging prongs one of which is of a taper formation, and thimbles 45 having a D shape in cross-section and the flat portions which are adapted to contact with the adjacent flat surfaces of the prongs to afford extended brazing-surfaces and a substantial attachment between the parts, substantially 50 as set forth.

3. A rear fork for cycles, comprising a plate connection formed with a guide-slot for the axle and with diverging prongs, each comprising a tongue portion and a semicircular 55 base and affording an abutment for the end of the thimble, and thimbles having a D shape in cross-section and the flat portions which are adapted to contact with the adjacent flat surfaces of the prongs to afford extended 60 brazing-surfaces and a substantial attachment between the parts, substantially as set forth.

4. A rear fork for cycles, comprising a plate connection formed with a guide-slot for the axle, and diverging prongs, each comprising 65 a tongue portion, a semicircular base affording an abutment for the end of the thimble, and a centering-stud, and thimbles having a D shape in cross-section and provided with ori-70 fices to receive the centering-studs, the flat portions of the D -shaped thimbles being adapted to contact with the adjacent flat surfaces of the prongs to afford extended braz-75 ing-surfaces and substantial attachments be-tween the parts substantially as set forth.

In testimony whereof witness my hand this 2d day of November, 1898.

ANTHONY JEROME.

In presence of—
ROBERT BURNS,
JAMES LAVALLIN.
